(57) **CLAIM**

The ornamental design for a display panel of a computing system having a graphical user interface for programming a robot as shown.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

The FIGURE is a front view of a display panel of a computing system having a graphical user interface for programming a robot.

The broken or dotted lines in the figure depict portions of the display panel of a computing system having a graphical user interface for programming a robot that form no part of the claimed design. The portions that form no part of the claimed design that are included in broken or dotted lines include, but are not limited to, the words in the figure.
